UNITED STATES PATENT OFFICE.

WILLIAM I. BUNKER, OF CHICAGO, ILLINOIS.

DESIGN FOR A BRACKET FOR SPRINGS.

SPECIFICATION forming part of Design No. 15,984, dated March 24, 1885.

Application filed January 27, 1885. Term of patent 14 years.

To all whom it may concern:

Be it known that I, WILLIAM I. BUNKER, a citizen of the United States, residing at Chicago, Illinois, have invented and produced a
5 Design for a Bracket for Coiled Springs, of which the following is a specification.

The object of my design is to furnish a bracket that will present in outline the form of a capital B.

10 In the accompanying drawings, Figure 1 is a perspective view of a bracket showing my design, and Fig. 2 a plan view thereof.

In illustrating a bracket, to embody my design and present the outlines of the capital letter B, I show the brackets double, and consisting of a main plate, two loops, and a web connecting the loops; but the web is not necessarily essential or indispensable, inasmuch as the design may be presented by a bracket
15 consisting of the main plate and two contiguous loops alone. The main plate may have a scalloped periphery and the loops be flanged, as shown.

I claim—

1. The design for a bracket presenting the 25 shape or configuration of the capital letter B, as shown, the same consisting of a main plate and two contiguous loops, substantially as described.

2. The design for a bracket presenting the 30 shape or configuration of the capital letter B, as shown, the same consisting of a main plate, two loops, and a web connecting the loops, substantially as described.

3. The design for a bracket presenting the 35 shape or configuration of the capital letter B, as shown, the same consisting of a main plate having a scalloped periphery, two loops, flanged as shown, and a web connecting the loops, substantially as described.

WILLIAM I. BUNKER.
